Robert S. Peelle INVENTOR

Frank J. Wentworth
his ATTORNEY.

UNITED STATES PATENT OFFICE.

ROBERT S. PEELE, OF HOLLIS, NEW YORK, ASSIGNOR TO THE PEELE COMPANY, OF BROOKLYN, NEW YORK, A CORPORATION OF NEW YORK.

ELEVATOR DOOR.

Application filed March 5, 1920. Serial No. 363,530.

To all whom it may concern:

Be it known that I, ROBERT S. PEELE, a citizen of the United States, residing at Hollis, in the borough of Queens, city of New York, county of Queens, and State of New York, have invented certain new and useful Improvements in Elevator Doors, of which the following is a specification, reference being had therein to the accompanying drawings, which form a part thereof.

My invention relates to elevator doors, and more particularly to a type of door having a metal frame carrying a metal sheathed wooden panel.

Heretofore in the art of fireproof elevator doors, it has been the common practice to secure the metal sheathed wooden panel to the iron angle frame of the door by means of ordinary stove bolts, with a flat washer interposed between the nut and the metal sheathing of the door. In this construction, the floor side of the door has unsightly projections thereon extending beyond the plane of the door, which projections also cause likelihood of injury to persons on the floor side of the door, or interference with objects close to the sill of the door. The use of the ordinary nut and washer also gives but a small gripping area for the nut with a resultant likelihood of loosening thereof through vibration of the door structure.

If it be desired to reduce the extent of the projection of the bolt structure from the door, it is necessary to cut off the end of the bolts beyond the nut, but even then the nut itself will project beyond the plane of the door to the extent of the thickness of the nut and the washer.

With these conditions in mind, I provide a door structure wherein the wooden panel will be secured to the angle iron frame in a manner to avoid the presence of any unsightly projections upon the floor side of the door, while permitting the wooden panel to be drawn tightly against the angle frame. The securing means employed is such as to readily imbed itself in the wooden panel and to co-operate with the metal sheathing in a way to form a fireproof joint, the enlarged flat head of the nut presenting a large bearing surface against the metal sheathed wooden panel. This nut is so formed as to readily penetrate the wood of the panel and

to wedge it apart in a manner to avoid the necessity for the formation of any counter-sinks, thus simplifying the assembling of the door and preserving the metal sheathing between the nut and the wood adjacent the surface of the door.

The invention consists primarily in an elevator door embodying therein a metal frame, a metal sheathed wooden panel, and means securing said panel to said frame comprising a screw bolt passing through said frame and said panel, and a nut having a truncated conical body adapted to penetrate the wood of the panel, and an enlarged head adapted to bear against the outer surface of the panel; and in such other novel features of construction and combination of parts as are hereinafter set forth and described, and more particularly pointed out in the claims hereto appended.

Referring to the drawings,

Fig. 1 is a section through a portion of the edge of a door showing one of the means for securing the wooden panel to the frame;

Fig. 2 is a perspective view of the nut upon an enlarged scale;

Fig. 3 is an end view of the nut from the head side; and

Fig. 4 is a side view of the nut, partly in elevation and partly in section.

Like letters refer to like parts throughout the several views.

In the embodiment of the invention shown in the drawings *a* indicates an ordinary angle frame for an elevator door having seated therein a wooden panel *b* covered by a metallic sheathing *c*. Registering holes *d* adapted to receive a stove bolt *d*, are drilled through one flange of said frame and through the adjacent portion of the panel and its sheathing.

Co-operating with the screw threaded end of the bolt *d* is a wedge nut, the body of which is adapted to penetrate the wood of the panel, and the head of which is adapted to bear upon or be pressed slightly within the face of said panel adjacent the floor side of the door.

The body *e* of this nut is of truncated, conical form, the smaller end thereof being brought to a narrow edge, in fact almost a knife edge. The head *f* of the nut is a wide flange formed integrally with the body *e*.

thereof and is provided with openings f' — f^2 adapted to receive a spanner wrench or other special tool for turning the nut.

The interior screw threads of said nut, 6 shown at g , pass completely through said body and said flanged top, said top, if desired, being provided with a slight countersink or chamfer, indicated at h , to permit the upsetting of the end of the bolt d to lock 10 the nut in place and avoid any substantial portion of the end of the bolt projecting beyond the head of the nut. This chamfered portion, however, is a mere matter of convenience, and is not essential to the invention, particularly as the frictional engagement between the outer face of the body of the nut, and the metal sheathing and the wood of the panel will minimize any likelihood of the loosening of the nut as a 15 result of vibration.

In assembling the door structure, the bolt d is passed through the registering openings in the frame a panel b and sheathing c with the screw threaded end thereof projecting slightly beyond the face of the panel 20 at the floor side of the door opening.

The reduced edge of the body portion e is then presented toward the door and the nut mounted upon the bolt and tightened 30 by means of a spanner wrench or special tool engaging the openings f' — f^2 .

If found necessary, the metal sheathing about the bolt d may be scored slightly to facilitate the starting of the nut, although 35 the pressure applied to the nut is ordinarily sufficient to break down this sheathing close to the bolt.

As the nut is tightened, the twisting movement thereof as well as the co-operating 40 screw threads will actually compress the fibers of the wooden panel and gradually force the metal sheathing inwardly so as to effectively protect the wood about the bolt d for a considerable depth.

45 The nut is tightened until the entire body thereof is well imbedded in the wood of the panel b and the head f thereof is partially or wholly imbedded in the surface of said panel.

50 The turning action of the nut will have a spinning effect upon the metal of the sheathing so that no cracks or breaks will be developed in the sheathing about the nut, thus ensuring against the exposure of the 55 wood through said sheathing.

When the nut has been tightened, the end of the bolt d may, if desired, be upset to lock the nut.

Since the body of the nut will engage the 60 bolt well within the surface of the panel, shorter bolts may be used than was heretofore possible, the end of the bolt projecting beyond the face of the panel being merely sufficient to ensure the proper engagement of the threads of the nut therewith,

there being little resistance offered to the nut during the initial stage of the penetration of the body thereof into the wooden panel.

An essential characteristic of the invention 70 is the use of securing means between the metal frame and the metal sheathed wooden panel, which in assembling the door will bring the nut structure substantially within the plane of the floor side of the panel without the necessity for forming countersinks in the material of said panel and without interrupting the metallic sheathing in a manner to interfere with the fireproof qualities 75 of the door.

It is not my intention to limit the invention to the precise details of construction shown in the accompanying drawings, it being apparent that such may be varied without departing from the spirit and scope of 80 the invention.

Having described the invention, what I claim as new and desire to have protected by Letters Patent, is:—

1. An elevator door embodying therein a 90 metal frame, a metal sheathed wooden panel, a bolt passing through said metal frame and said panel, and a nut having a body portion imbedded in the wood of said panel, and an enlarged head bearing upon the surface thereof, whereby the wooden portion of the panel is compressed about said body portion and the metal sheathing of the panel is deformed by and interposed between a portion of said body portion of the nut 95 and the wood of the door.

2. An elevator door embodying therein a metal frame, a metal sheathed wooden panel, and means securing said panel to said frame comprising a screw bolt passing through 105 said frame and said panel, and a nut having a truncated conical body penetrating and compressing the wood of the panel and deforming the metal sheathing and holding it interposed between a portion of said conical body and the compressed portion of the wood, and an enlarged head bearing against the outer surface of the panel.

3. An elevator door embodying therein a metal frame, a metal sheathed wooden panel, 115 and means securing said panel to said frame comprising a screw bolt passing through said frame and said panel, and a nut having a truncated conical body reduced to a narrow knife-like edge at the smaller end thereof, 120 penetrating and compressing the wood of the panel and deforming the metal sheathing and holding it interposed between a portion of said conical body and the compressed portion of the wood, and an enlarged head bearing 125 against the outer surface of the panel.

4. An elevator door embodying therein a metal frame, a metal sheathed wooden panel, and means securing said panel to said frame comprising a screw bolt passing through 130

said frame and said panel, and projecting slightly beyond the latter, and a nut having a truncated conical body penetrating and compressing the wood of the panel and defining the metal sheathing and holding it interposed between a portion of said conical body and the compressed portion of the wood, and an enlarged head bearing against the outer surface of the panel, said nut having a screw threaded opening extending longitudinally of said body and opening outwardly of said head, said enlarged head

being provided with means whereby a tool may be applied thereto for tightening said nut.

15

In witness whereof I have hereunto affixed my signature, in the presence of two subscribing witnesses, this 18th day of February, 1920.

ROBERT S. PEELLE.
